UNITED STATES PATENT OFFICE.

HARRY TROUTS, OF BRIDGEPORT, CONNECTICUT.

ANVIL ATTACHMENT.

1,349,927.

Specification of Letters Patent. Patented Aug. 17, 1920.

Application filed September 25, 1918. Serial No. 255,642.

To all whom it may concern:

Be it known that I, HARRY TROUTS, a citizen of the United States, residing at Bridgeport, in the county of Fairfield, State of Connecticut, have invented certain new and useful Improvements in Anvil Attachments; and I do hereby declare the following to be a full, clear, and exact description of the invention, such as will enable others skilled in the art to which it appertains to make and use the same.

This invention relates to new and useful improvements in anvils and particularly to attachments for anvils.

One object of the present invention is to provide a novel and improved attachment for an anvil whereby the welding of chain links can be quickly and easily accomplished without the necessity of the provision of a special anvil.

Another object is to provide a novel and simple device which can be easily and quickly applied to the horn of any ordinary anvil whereby the smith is relieved of the expense of buying a special anvil, thus readily converting the anvil into one for the special purpose of welding chain links.

Other objects and advantages will be apparent from the following description when taken in connection with the accompanying drawing.

In the drawing:

Figure 1 is a side elevation of an anvil having the attachment thereon, and partly broken away.

Fig. 2 is a bottom plan view of the attachment removed from the anvil.

Fig. 3 is a vertical transverse sectional view taken on the line 3—3 of Fig. 1.

Referring particularly to the accompanying drawing, 10 represents an anvil which has the horn 11, and in connection with which my invention is particularly adapted for use.

In welding chain links it is necessary to slide the link onto the horn of the anvil, but in so doing the link which is engaged through the one on which work is being performed engages against the lower face of the

horn and thus prevents the proper positioning of the work link on the horn. In some anvils there is provided a longitudinal groove in the lower face of the horn to receive the upper part of the second link, as seen in the patent to J. E. Campbell, 1,065,918, issued July 1, 1913. Smiths

already have their anvils in their shops and do not care to be put to the added expense of buying another anvil which has the groove, and it is with this particular object in view that the present device is invented.

The invention consists of a member 12 which is of the same outline as the horn of the anvil, but is slightly larger size and hollow so that it can be easily slipped onto the horn and fit thereon snugly. In the lower face of the member 12 there is formed a longitudinal groove 13 which receives the upper portion of the next lower link of the chain. Extending upwardly through the member 12 and in the groove, is a screw 14 which is arranged to be turned upwardly into biting engagement with the lower face of the horn of the anvil, whereby the member 12 will be firmly held in proper position on the horn. The lower portion of the member 12 is necessarily thicker than the upper portion for the purpose of forming the groove therein. This groove extends through the end of the member 12 so that the links can be slipped on from the end of the attachment.

By means of this attachment, which is extremely simple and cheap in construction, the smith can quickly and easily convert his ordinary forge anvil into an anvil which will permit the welding of chain links. Thus the smith is permitted to possess a device which is valuable in itself as a working expedient and without the expense of providing himself with a separate and special kind of anvil.

What is claimed is:

As an article of manufacture an attachment for an anvil comprising a hollow tapering body of an external outline the shape of the horn of an anvil, and an internal outline and size to snugly fit the horn of an anvil, the outer face of the body having a longitudinal groove extending through the smaller end of the body and terminating adjacent the larger end of the body, and a screw engaged through the last-named end of the groove, said grooved portion of the body being thicker than the remainder thereof.

In testimony whereof I affix my signature in the presence of two witnesses.

HARRY TROUTS.

Witnesses:

ANDREW LIGHTCAP,
THEO. M. MOYER.
